UNITED STATES PATENT OFFICE.

LOUIS STOCKSTROM, OF ST. LOUIS, MISSOURI, ASSIGNOR TO AMERICAN STOVE COMPANY, OF ST. LOUIS, MISSOURI, A CORPORATION OF NEW JERSEY.

OIL-STOVE.

1,103,703.

Specification of Letters Patent. Patented July 14, 1914.

Application filed October 27, 1913. Serial No. 797,663.

To all whom it may concern:

Be it known that I, LOUIS STOCKSTROM, a citizen of the United States, residing at St. Louis, in the State of Missouri, have invented certain new and useful Improvements in Oil-Stoves, of which the following is a specification, reference being had therein to the accompanying drawing.

My invention relates to improvements in oil stoves.

The object of my invention is to provide an oil stove in which the burners can be readily moved outwardly from beneath the top of the stove and supported for the purpose of cleaning or re-wicking without disconnecting the burners from the oil tank.

Another object of my invention is to provide a simple, cheap and more effective means to accomplish this result and having 20 certain details of structure hereinafter more fully set forth.

In the accompanying drawing: Figure 1 is a front elevation of my improved oil range embodying my invention and shown partly 25 in section to show the supporting means in the movable burner supporting pan. Fig. 2 is a detached perspective view of the burner supporting pan partly broken away and showing the specific means for supporting 30 the oil tank.

Referring now to the drawings, 1 represents the base of my improved oil stove, which, as shown, is supported by the legs 2. Carried by the upper face of the base 1 are 35 standards 3, supporting the top 4 of the stove. While I have shown my device as applied to an oil range, it will be understood that the same principle can be applied to a one, two or three burner stove without deviating from my invention. In the form 40 shown supported by the top 4 is the oven 5, arranged at one side of the heating burners 6 and 7. Below the oven 5 are the two burners 8 and 9, constructed precisely like the 45 burners 6 and 7 and are intended to heat the oven 5, as clearly shown in Fig. 1 of the drawings.

The base 1 is provided at each end with a plate 10, having at its upper end the inwardly turned flange 11, and secured to the lower face of the plate 10 is a strip 12 and the space 13 between the inwardly turned flange 11 and the strip forms a guide for the movable pan 14. Each end of the base

is provided with plates 10 and strips 12 to 55 form guides at each end, as will be herein-after more fully described. The rear standards form stops to limit the inward movement of the pan, whereby the burners are in their proper positions when the pan is 60 moved inwardly.

The pan 14, as shown, is of a length equal to the space between the plates 10 and of a width equal to that of the base 1, and is formed of a flat sheet of metal having at its 65 ends the upwardly turned flange 16, and at the rear edge an upwardly turned flange 17. The flange 16, as shown in Fig. 1 of the drawing, is of a width equal to the space between the plate 11 and the strips 12, whereby 70 the pan can be easily moved in or out within the guide-way 13, as shown in Fig. 1 of the drawings.

The pan 14, adjacent its ends, is provided with brackets 18 and 19, in which is mounted 75 an oil-supply pipe 20, carrying the burners 6, 7, 8 and 9. This pipe is rigidly supported by the brackets 18 and 19 and likewise the burners 6, 7, 8 and 9 are rigidly supported by the pipe, and when the pan is in its inward position, the burners are in their proper position in respect to the top 4 and the oven 5 of the stove. The pipe 20 beyond the bracket 19, is provided with a 80 crank 21, which is turned outwardly as indicated at 22, and is further supported by a bracket 23, carried by the bottom of the pan 14. The bracket 23 has an upwardly extending arm 24, which supports a pan or bracket 25, in which is supported a glass oil 90 tank 26. The outer end of the pipe 22 has a removable connection 27, which has its outer end rigidly connected to the tank supporting pan 25.

The oil from the tank 26 is fed through 95 the connection 27 and the pipe 22 to the pipe 20. The pipe 20 has separated connections 28, 29, 30 and 31 with the respective burners 6, 7, 8 and 9, for supplying the burners with oil, as is well understood by those skilled in the art. The tank 26 is also located so that the oil is fed by gravity to the burners, which is clearly shown in Fig. 1 of the drawings.

From the foregoing description it will be 105 seen that the tank and all the burners are supported by the pan 14 and the crank 21 of the oil-supply pipe 20 is set back adjacent

the rear edge of the pan, so that the pan can be moved outwardly until the straight portion 22 of the oil-supply pipe 20 strikes the standard 3 adjacent thereto. When the pan 5 has been moved outwardly so that its movement is limited by the pipe 22, the burners are in a position beyond the top 4, of the stove, so that they can be readily cleaned or new wicks placed therein.

10 While I call the member 14, a pan, it will be understood that this could be made in a flat plate or an iron rack or frame-work without departing from my invention.

By this construction it will be seen that 15 all of the burners are simultaneously moved outwardly from beneath the top of the stove and the tank is likewise moved outwardly, thus preventing the breaking of joints or the disconnection of the tank from the burners when it is desired to clean the burners or replacing the wicks. While I have shown and described this specific form for accomplishing my results, it will be understood 20 that the same can be varied without departing 25 from my invention.

Having thus described my invention, what I claim and desire to secure by Letters Patent is:

1. The combination with a stove, of a 30 movable member supported thereby, burners supported by said movable member, an oil supply pipe for supplying oil to the burners having a rearwardly extending portion above the movable member, and having 35 its outer end turned outwardly beyond the end of the stove and an oil tank supported by the outer end of said pipe whereby the movable member may be drawn outwardly to bring the burners from beneath the top of 40 the stove.

2. The combination with a stove, of a 45 movable member supported thereby, an oil supply pipe extending across the member, burners supported by said pipe, one end of the said pipe having a rearwardly extending portion above the movable member having 50 its outer end turned outwardly, an oil tank supported by the outer end of the said pipe beyond the end of the stove, whereby the movable member may be drawn outwardly to bring the burners from beneath the top of the stove.

3. The combination with a stove, of a 55 lighting member carried thereby, burners supported by the said member beneath the top of the stove, an oil supply pipe for the said burners having one end extending rearwardly above the member and having its extreme outer end turned outwardly, and a 60 tank supported by the outer end of the said pipe beyond the end of the stove, whereby the removable member may be drawn outwardly to bring the burners out from beneath the top of the stove.

65 4. The combination with a stove, of a slid-

ing member supported by the stove, brackets supported by the member, an oil supply pipe supported by the brackets, burners supported by the oil supply pipe and receiving oil therefrom, a crank-shaped pipe connected to one end of the oil supply pipe and extending rearwardly and outwardly beyond the end of the stove, means carried by the member for supporting an oil-supply tank beyond the end of the stove, a connection between 70 said tank and the crank-shaped pipe whereby the member may be drawn outwardly to bring the burners out beyond the top of the stove, said member being supported at all times in a horizontal position. 75

5. The combination with a stove, of channel-shaped guideways at each end thereof, a member having upwardly turned flanges fitting within said guideways, brackets carried by the member, an oil supply pipe carried 85 by the brackets above the member, burners supported by the oil supply pipe and receiving oil therefrom, a crank-shaped pipe connected to the oil-supply pipe and extending rearwardly and outwardly beyond the end 90 of the stove, a bracket carried by the member and extending outwardly, a tank supported by the bracket and connected to the crank-shaped pipe whereby the member may be drawn outwardly to bring the burners 95 out beyond the top of the stove, substantially as shown and described.

6. The combination with a stove, of a sliding member carried thereby, an oil supply pipe carried by the member, burners 100 supported by said pipe, combustion tubes carried by the burners, and having their upper ends below the horizontal plane with the top of the stove, a crank-shaped pipe connected to one end of the oil supply pipe, 105 and extending outwardly beyond the end of the stove, an oil supply tank carried by said crank-shaped pipe beyond the end of the stove, whereby the sliding member can be moved outwardly substantially as shown 110 and described.

7. The combination with a stove, of a sliding member supported thereby, brackets supported by the members, burners supported by the brackets, a crank-shaped pipe connected to the burners and extending rearwardly and outwardly beyond the end of the stove, a tank supported by the movable member beyond the end of the stove and in rear of a vertical line with the burner and 115 connected with the crank-shaped pipe whereby the movable member may be drawn outwardly to bring the burners from beneath the top of the stove for the purpose described.

8. The combination with a stove, of a sliding member carried thereby burners supported by said sliding members, combustion tubes carried by the burners and having their upper ends below a horizontal plane 120

125

130

with the under face of the top of the stove, a crank-shaped pipe carried by the sliding member and extending rearwardly and supplying oil to the burners and extending outwardly beyond the end of the stove, and an oil supply tank carried by the outer end of the crank-shaped pipe beyond the end of the stove, whereby the sliding member can be moved outwardly to bring the burners from beneath the top of the stove, substantially as 10 shown and described.

In testimony whereof I hereunto affix my signature in the presence of two witnesses.

LOUIS STOCKSTROM.
